US0D1046828S

(12) **United States Design Patent** (10) **Patent No.:** **US D1,046,828 S**
(45) **Date of Patent:** **** Oct. 15, 2024**

(54) **CONFERENCE MICROPHONE**

(71) Applicant: **SHENZHEN EMEET TECHNOLOGY CO., LTD.**, Shenzhen (CN)

(72) Inventor: **Wenming Chen**, Shenzhen (CN)

(**) Term: **15 Years**

(21) Appl. No.: **35/518,923**

(22) Filed: **Nov. 7, 2022**

(80) **Hague Agreement Data**

Int. Filing Date: **Nov. 7, 2022**

Int. Reg. No.: **DM/224932**

Int. Reg. Date: **Nov. 7, 2022**

Int. Reg. Pub. Date: **Nov. 10, 2023**

(51) **LOC (14) Cl.** **14-01**

(52) **U.S. Cl.**

USPC **D14/225**; D14/150; D14/228

(58) **Field of Classification Search**

USPC D14/150, 155–159, 160–174, 187–188, D14/189–199, 203.1–203.8, 204–216, D14/217–222, 223, 224–229, 356–358, D14/492, 496–497, 498–506; D13/108, D13/110, 123, 133–135, 162; D3/273, D3/294, 295

(57) **CLAIM**

The ornamental design for a conference microphone as shown and described.

DESCRIPTION

1. Conference microphone
  - 1.1: Perspective view;
  - 1.2: Front view;
  - 1.3: Back view;
  - 1.4: Left view;
  - 1.5: Right view;
  - 1.6: Top view;
  - 1.7: Bottom view;
  - 1.8: Perspective view; and
  - 1.9: Enlarged view of portion labeled, “1.9.” in 1.1.
1. The dash-dash broken lines in the drawings depict the portions of the conference microphone that form no part of the claimed design.

(Continued)

1.9

2. The dot-dash broken lines in the drawings depict the boundaries of the enlarged views and form no part of the claimed design.

1 Claim, 9 Drawing Sheets
